UNITED STATES PATENT OFFICE.

CHARLES M. NEELD, OF PITTSBURGH, PENNSYLVANIA.

FORM OR MOLD.

1,109,863.

Specification of Letters Patent.

Patented Sept. 8, 1914.

Application filed January 16, 1913. Serial No. 742,386.

To all whom it may concern:

Be it known that I, CHARLES M. NEELD, a citizen of the United States of America, residing at Pittsburgh, in the county of Allegheny and State of Pennsylvania, have invented new and useful Improvements in Forms or Molds, of which the following is a full, clear, and exact description, reference being had to the accompanying drawings, which form a part of this specification.

This invention is an improvement in molding forms for the building of walls, floors or other structures of concrete, cement or other plastic material, as by molding the structure *in situ*.

The general object of the invention is to provide preferably a sectional mold, which may be so adjusted or built up as to adapt it to the different requirements or contingencies of service; which shall be light in weight, easy to handle, and which can be quickly and conveniently assembled or built up and disassembled.

With the above object in view, I aim to provide a mold employing in its construction preferably an operative molding face constructed of thin sheet metal. I so reinforce this sheet metal as to prevent it from warping or skewing out of shape under handling and use thereof, thereby maintaining true alinement of the molding face or wall. While I preferably form this sheet metal form in unit lengths adapted for articulate assembling, a tight joint is afforded between the several sections in such manner as to not only provide an uninterrupted operative molding surface or face, but to also prevent leaking and reduce the formation of wall-fins, ribs, etc.

I will now describe my invention referring to the accompanying drawings, so that others skilled in the art, may understand and construct the same, it being premised, however, that various changes may be made in the different embodiments of my invention shown and described, without departing therefrom, and I do not, therefore, desire to limit myself thereto.

Figure 1 is a fragmentary perspective sectional view illustrating a wall mold embodying my invention, the sheet metal section being provided with intermediately disposed reinforcing flanges or ribs, to be hereinafter more fully described; Fig. 2 is a sectional view showing a modified manner of joining contiguous sections; Fig. 3 is a

similar view showing the mold wall proper as composed of narrow separately formed sections; Fig. 4 is a sectional view illustrating one manner of applying a reinforcing element to the sheet; Fig. 5 is a similar view showing manner of applying a reinforcing element at the point of union of two separate contiguous sheet sections; Fig. 6 is a sectional perspective view showing one section telescoped interlocking with another section for varying lengths without cutting; Figs. 7 and 8 are sectional views showing manners of reinforcing the molding sheets, and to be hereinafter more fully described; Fig. 9 is a fragmentary sectional perspective view showing application of my improved mold to the formation of beams, columns and similar structures, as will be hereinafter more fully described; Figs. 10 and 11 are fragmentary sectional views illustrating a reinforcing brace or bar, which may be used in connection with the mold sections, as will be hereinafter set forth; and Fig. 12 is a modified form of providing for end lap or nesting of the section.

In the embodiments of my invention as illustrated, I preferably employ a sheet metal member 2 which constitutes the operative molding face of the wall, and I so reinforce this sheet as to enable me to employ very thin and light weight sheet metal. The member 2 may be formed of galvanized sheet iron or any suitable sheet metal.

Referring more particularly to Fig. 1, the section 2 is shown as comprising a plate 3, having the intermediate L-shaped folds 4, which run lengthwise of and serve to stiffen the section and which are at substantially right angles to the face of the section. At the ends or longitudinally of the edges of the sheet these members 4 are preferably formed of only a single thickness of metal, so that in assembling of the different molding sections, the said members 4 will interlock with one another and provide in their union a reinforcing flange or rib equal in thickness to that of the intermediate members 4. As stated, the members 4 are preferably formed by folding the sheet; and to prevent the fold from spreading and thereby interrupting the continuity of the operative face of the mold, suitable clamping means 5 are provided to firmly clamp the sheet preferably at the fastening point where the members 4 pass from the main body portion thereof. Such clamping or fastening means may con-

sist of bolts and nuts or rivets, or the sheet may be welded at this point, as by electric spot welding, to effect the union spoken of. The depending portion 6 of the reinforcing flange 4, not only serves to stiffen the flange at the rear against deflection or distortion in handling and under strains but also provides a convenient flat attaching flange for reinforcing or tying straps 7 which extend transversely across the sheet and serve to stiffen the section; said strap being attached to the flanges 6 in any desirable manner, such as by rivets or like fastening means or by welding, if desired. It will also be noted that the depending portions 6 form a wide, flat bearing face for the studs or joists 8, obviating a liability of injurious kinking or deflection of the reinforcing flanges of the sheet, in application of the studs and in the exertion of pressure there against due by introduction of the concrete or plastic material within the form. However, the flanges 6 also perform another function in that they may act as guides or stops for such interlocking of the edges of continuous sections as will operate to bring the molding face of one of the sections of the mold wall into alinement with that of the other. To enable proper interlocking of the sections, the strap 7 preferably is secured to the inside of the depending top flange 6', so that the end of said strap will not obstruct proper nesting of the foot or flange 6^a of the next adjacent section, which flanges 35 preferably assumes an outer overnesting position.

In setting up the mold sections, any suitable backing or main reinforcing posts, bars or beams may be employed, as is usual in the erection of molding formations of this general character. However, as shown in Figs. 1, 10 and 11, I may employ a primary backing or reinforcing member 8, comprising suitable conventional sections 9, which may be formed in short lengths to facilitate assembling and ready re-setting of the mold sections. For instance, as shown in Figs. 10 and 11, the members 9 may overlap and be united by suitable fastening means 10 comprising studs carried by one member and adapted to be tied to the web of the other member, as by tapered wedge keys 11 passing therethrough. By employing wedge keys, the sections may be readily disconnected when it is desired to remove or otherwise shift or adjust said sections. At the point where one section 9 joins the other, the members are preferably so spaced as to provide an intermediate opening or pocket 12, through which a tie rod 13 may be passed; such tie rods being usually employed to lock opposing sections of a mold in proper position against displacement or distortion in applications or setting of the plastic material. The tie rods may also carry a suitable

reinforcing brace of commercial sections 14, such as channels placed back to back running transversely and back of the reinforced sections 8, said tie rod being provided with the usual clamping nut 15. The reinforcing members 8 may be of any suitable shape such as the channels shown or an angle section Z bar, or similar structure. Such structures are usually employed not only because of the great stiffness afforded with the minimum of metal but also because of the provision of thin web or flange portions to which auxiliary pieces, such as the sections 16, may be attached where the requirements or exigencies of the case demand it. 80

Any suitable means may be employed for tying the mold section to the reinforcing posts or members 8. For instance the L-shaped flanges 4 may have suitable hole openings or eyes 17, through which a flexible tie member such as wire, may be passed, and by which the section may be securely anchored to said studs or joist or section 8.

The contiguous sections may be united to one another in different ways. For instance, as illustrated in Fig. 2, the end or edge reinforcing flange 4 is shown as having the continuation 18, which may be spread from the wall 19 sufficiently to permit of the interpositioning or interlocking of the large angular flange 20 of the adjoining section; the member 18 having an angular flange 21 which serves to readily guide the flange 20 upon insertion thereof between the portions 18 and 19. 100

As illustrated in Fig. 3, the mold section 3 is shown as being formed of a plurality of separate sections 3, which may be united by suitable fastening means 5 and tied to the strip 7, as in the case of sections as shown in Fig. 1. 105

In Figs. 4 and 5, I show modified means for providing a light reinforcing member 4' corresponding in function to the member 4 described in connection with Fig. 1. As shown in Fig. 4, the sheet 2 has a comparatively short fold 4^a, which not only serves to reinforce the sheet but also provides fastening means in application of the angle member 4^b thereto. In Fig. 5, I illustrated the section 4' as having secured thereto the two separate sections 2^a, instead of providing the continuous fold as shown in Fig. 4. In referring to both of these views, it will be understood that the fastenings 5 are preferably so positioned near the body of the sheet as to prevent opening of the sheet at the molding face thereof. 110 115 120

By referring to Fig. 6, it will be seen that by my improved mold, sections may be readily locked as to enable convenient and ready longitudinal adjusting of the sections in the building up of the mold or disassembling thereof. And as brought out in Figs. 1 and 12 the ends of the sheets may have the ex- 130

tensions 22 or lap formed in the integral with the sheet or comprising a separate piece 24 connected to the body of the sheet, as shown in Fig. 12; the purpose of said extensions being to afford a lap for end interlocking of the sheets as they are assembled.

In Fig. 7, I indicate a modified manner of reinforcing the molding sheet 2. It consists in providing an irregular backing sheet or strip 23 in lieu of the flanged members 4 above described. In this case, the member 23 is shown as being substantially a corrugated sheet to which may be applied the stiffening strips 7, above described.

In Fig. 8, another form of reinforcement is shown. It comprises the Z-bar 24, to which may be riveted or otherwise applied the sheet 2. This Z-bar construction has the advantages of the L-reinforcement shown in Fig. 1, in so far as concerns its reinforcing quality and convenience of attachment to the auxiliary reinforcing means or bracing posts or bars. Instead of employing a Z-bar, a channel shape 24" may be used in lieu thereof, as shown in this view.

It will be apparent from the foregoing description that in building up the mold, said mold may take different shapes in accordance with the requirements of the particular structure contemplated. By reason of the simplicity of construction, lightness of weight and the facility of adjustment, there is practically no limit in the formation of desired molding shapes. For instance, as shown in Fig. 9, a plurality of mold sections 25, constructed in accordance with my invention may be employed in conjunction with suitable angle corner pieces 26, in forming beams, columns, etc.; the corner section 26 permitting of relative adjustment of the main mold sections 25.

The advantages of my invention will be appreciated by those skilled in the art. I not only provide a mold in which simplicity of construction and minimum amount of metal obtain, but also a mold which may be easily set up and taken down.

Instead of the conventional rolled shapes shown, such sections may be rolled or pressed up out of sheet metal.

Having thus described my invention, what I claim and desire to secure by Letters Patent is:

1. In a mold of the character described, a wall composed of a plurality of sections, each section consisting of a wall portion formed of sheet metal and a plurality of angularly projecting reinforcing integral flanges, having end folds extending at an angle to the plane of the flanges.

2. In a mold of the character described, a

wall composed of similar sections, each section consisting of a wall portion formed of sheet metal and a plurality of flanges angularly disposed along the section and each comprising an intermediate flange and a longitudinal edge flange on said intermediate flange at an angle thereto formed by folding the body of the sheet metal.

3. In a mold of the character described, a wall composed of similar abutting sections, each section consisting of a wall portion formed of sheet metal and having a plurality of integral flanges along its length and angularly disposed with regard to the body of the sheet, said plurality including end flanges interlocking with end flanges of an adjacent section and also including flanges formed by a fold of metal of the sheet and intermediate said end flanges, and separate means for reinforcing the sections.

4. In a concrete form section, a mold wall section of thin sheet metal carrying a plurality of reinforcing flanges at its back, each such flange being formed by an L-shaped double fold of the sheet metal, and a plurality of tie strips secured to the ends of the flanges.

5. In a wall mold for concrete, a mold face comprising a plurality of abutting sections of sheet metal, each sheet of metal being folded to produce an L-shaped bracing flange having a part in a plane parallel to said sheet and vertical connecting means for said parts.

6. In a mold, a mold wall formed of a plurality of sheet metal sections in abutting engagement, each such section having lateral L-shaped integral flanges at each end adapted to engage the corresponding flange of an adjacent sheet and also adapted to engage with stiffening elements parallel to the plane of the sheets.

7. In a mold, a mold wall formed of a plurality of sheet metal sections in abutting engagement, each such section having lateral L-shaped integral flanges at each end adapted to engage the corresponding flange of an adjacent sheet and also adapted to engage with stiffening elements parallel to the plane of the sheets, each such section also having an integral flange extending at substantially right angles to such section and formed by a fold of the metal intermediate its ends.

In testimony whereof, I have hereunto set my hand.

CHARLES M. NEED.
